UNITED STATES PATENT OFFICE.

CHARLES E. WILLIAMS, OF CHICAGO, ILLINOIS, ASSIGNOR TO WILLIAMS ARTICULATOR COMPANY, A CORPORATION OF SOUTH DAKOTA.

PORTABLE AUDIPHONE-TRANSMITTER.

1,311,430.

Specification of Letters Patent. Patented July 29, 1919.

Application filed October 3, 1917. Serial No. 194,455.

To all whom it may concern:

Be it known that I, CHARLES E. WILLIAMS, a citizen of the United States, and resident of Chicago, in the county of Cook and State 5 of Illinois, have invented an Improvement in Portable Audiphone-Transmitters, of which the following description, in connection with the accompanying drawings, is a specification, like letters on the drawings representing 10 like parts.

My present invention is an improved transmitter, constituting a hearing aid for deaf or partially deaf persons, and is intended primarily for use as a portable instrument in connection with the well known 15 type of hearing aids known as the Williams audiphone.

The manufacture of portable instruments to aid hearing, presents many difficulties, 20 particularly in the arrangement, construction, efficiency and sensitiveness of the transmitters employed. It will be appreciated that all types of hearing aids intended to be carried by the person must be compact and 25 suitable for transporting and yet must be extremely delicate, accurate and capable of operation with a relatively small amount of electrical energy. In the manufacture of such transmitters, particularly, difficulty has 30 been experienced because of the size and depth of instrument heretofore necessary for efficient use. With the ordinary type of transmitter, if made shallow and of circular form, a nasal or thin sound was the result, 35 which was very objectionable to the user, and was unsuitable for use at any great distance. Furthermore, in such prior transmitters, if it was desired to employ two double transmitters, to produce a powerful 40 four transmitter instrument, the extreme bulkiness resulting was objectionable for a portable device.

My present invention not only enables me 45 to produce a very thin and compact transmitter, but also, by reason of the improved features of construction, to be explained, I have discovered that such thin transmitter can be so made as to successfully eliminate the objectionable nasal sounds above mentioned. In fact, I can make so compact a 50 transmitter that same may be formed with two double transmitters hinged together, thus constituting a four-transmitter instru-

ment of great power and efficiency, which will yet be so thin and compact that it can 55 be carried in an inside coat pocket, when used by men, or in the ordinary small shopping bag, when used by women, and the transmitter need not be removed from either receptacle during use. I accomplish this 60 result by utilizing a thin, relatively oblong and flat aluminum plate on either side of relatively shallow, circular transmitters, which oblong plates are covered with leather, 65 fabric or suitable textile material, turning under the plates the edge of the leather or fabric, which leather or fabric cushions the transmitter, thus allowing for a certain resiliency, which, in practice, prevents the lighter outside mechanical noises from interfering with the transmission of articulation. The advantages of this construction 70 seem to entirely eliminate the objectionable roaring or "sea shell sound" which was heretofore present in certain transmitters 75 of sufficient depth to secure the proper amount of reverberatory space therein. Furthermore, the oblong construction permits a considerable range or scope in varying the 80 transmitters by changing the tone and character of the same and of the sound transmitted, by making chambers longer or wider without increasing the depth. Thus the thin and compact arrangement of my improved transmitter is preserved and enables 85 the same to be carried in the pocket or shopping bag, as above explained. When it is realized that heretofore a four-transmitter audiphone was necessarily so bulky as to require a separate box and handle to carry it, 90 being approximately eight inches long, eight inches wide and four inches deep, whereas my invention permits a four-transmitter audiphone of equal power and greater sensitiveness to be constructed of a size capable 95 of fitting within the inside coat pocket, the practical importance of my present invention will be emphasized. I believe that both the form and construction of my transmitter shown herein is distinctly new, and therefore I wish to claim all novel features there- 100 of broadly.

Other features of the invention, details of construction and novel combinations of parts, will be hereinafter more fully pointed 105 out and claimed,

Referring to the drawings, illustrating a preferred embodiment of the invention,

Figure 1 is a front view, with the outer covering partly broken away, of my thin 5 oblong double transmitter;

Fig. 2 is a side view of the same;

Fig. 3 is a cross sectional view on the line 3—3 of Fig. 1; and

Fig. 4 is a diagrammatic view on a reduced scale, of the four-transmitter instrument.

Figs. 5 and 6 are front and side views, the latter in cross section, of a modified form of the invention.

15 I have herein illustrated, in the drawings, a double transmitter, but it will be appreciated that I may hinge together two of these thin oblong casings, each containing a double transmitter, folding the same equally 20 and thus producing a powerful four-transmitter instrument, with only double the thickness. In my completed four-transmitter instrument as now made, the entire thickness of the same is usually under two 25 and a half inches, whereas the width of the apparatus would be under four inches and the length approximately six inches.

The double transmitter, substantially as shown in the drawings, with one above the 30 other, in the oblong casing, gives an extremely satisfactory, delicate and efficient device, and it is also feasible to make this type of transmitter with a single instrument of half the length of the apparatus shown.

35 I prefer to arrange the instrument, with the double transmitters as shown, having said transmitters facing the oblong reverberatory chamber in the main casing, said transmitters being carried by the front plate 40 or cover which is spaced from the main casing, or back of the device, to form a reverberatory chamber, with means to permit the entrance of the sound waves into the oblong reverberatory chamber.

45 I prefer to use aluminum for the plates, covering the same with leather, although other suitable material in place of said aluminum plates may be employed, and any desired fabric may be utilized.

50 Referring to the drawings, the main casting or back of the instrument comprises an aluminum plate 1, which is fitted into the corresponding groove or recess 2 in the rim 3, so as to prevent a flush appearance on the 55 back, which is entirely covered by the leather or textile material 4. The rim 3 is also provided with a rabbet, as indicated at 5, around which the covering 4 is glued or held. This arrangement, 5, presents a 60 shoulder for the plate 6, also covered with leather or fabric 7, around its edges, which plate 6 carries the transmitters 8 and 9. The cover 10 is also incased in leather or fabric 11 having the ends of the same doubled over as indicated at 12 and 13 sufficient 65

so as to rest upon the shoulders of the transmitters 8 and 9, as clearly shown in Fig. 3. The usual binding posts 14, 15, are shown with connections 16, 17.

Through the plate 6 is a plurality of holes 18, 19, formed mainly and principally to permit the plate 6 to vibrate freely, affording a free air passage through the holes 18 in the plate 6, as indicated by the arrows 20, into the long oblong reverberatory 75 chamber 19. By having the transmitter-carrying plate 6 secured to the oblong member 1 around the edge of the rabbet 5 and the thicknesses of the leather covering 4 and 7, extraneous noises are eliminated, and the 80 accuracy, efficiency, and delicacy of the instrument is improved. The plates are held together by suitable screws 21, 21, and the handle 22 is also provided.

As already explained, the construction of 85 my improved transmitters, enables a considerable change in tone to be secured by simply enlarging the area of the transmitters without changing the depth, and the construction of the two plates 1 and 6, with 90 a yielding material, such as leather or fabric, interposed between their edges, whereby the transmitters are held spaced from the back 1 and each transmitter opens into the same reverberatory chamber 19, presents a construction which is compact, thin, and at the 95 same time produces a clear and powerful tone, eliminating all "roaring" and enabling a specially attractive, portable device to be made.

100 Also, where a powerful four-transmitter instrument is made in accordance with my invention, it is still sufficiently compact to be portable in a convenient way. By having the device covered with leather or textile material, an attractive and protecting 105 finish is given, while the use of the covering as the yielding and tightly compacting means between the two aluminum sheets, gives desired resiliency and improved action 110 to the apparatus.

115 In Figs. 5 and 6 I have illustrated a modification of the invention as applied to a different type of transmitter, such for example, as that shown in my prior Patent No. 911,101. In this form I employ a closed reverberatory chamber, with a plurality of 120 openings into the casing of the transmitter, and furthermore I subdivide the closed reverberatory chamber for each transmitter, the 125 partition thus subdividing the same being capable of varying the character of the sound by differently placing the partition as desired. As shown in Fig. 6, the transmitters in this form of the invention, 25 and 26, are held by a thin metallic plate 27, similar to the plate 6, in Fig. 3, which is attached around its side to the rim 28 and cover 29, all being inclosed with a leather casing 30. A plurality of perforations 31 130

around the entire periphery of the plate 27, are here shown in preference to a series of perforations around each transmitter, as in the prior construction. This permits the 5 vibration of the transmitters and of the entire plate 27, admitting air through the holes 31 into the reverberatory recess 33. The back plate 34 is also provided, being spaced from the holding plate 27 by a rim 10 35, extending around the edge portions, and forming a second reverberatory chamber 36, a plurality of holes or openings 39 in the transmitters 25 and 26 upon the electrode into this chamber 36. I prefer to add an 15 intermediate partition 40, dividing the chamber 36 into two separate portions, one for each transmitter and by varying the position of this partition I can secure a considerable change in the characteristics of the 20 sound.

In both forms a neat, compact double transmitter is provided in an extremely narrow space, and a four-transmitter instrument may be made which is still sufficiently 25 compact for convenient portability.

My invention is further described and defined in the form of claims as follows:

1. In a device of the kind described, the combination of a plurality of transmitters 30 in a reverberatory chamber, a plate carrying said transmitters and having openings around its edge permitting vibration of said plate, freely, by allowing access of the air to and from the under part of the plate said 35 plate forming part of the reverberatory

chamber, said transmitters being in substantially the same plane.

2. In a device of the kind described, the combination of a plurality of transmitters in a reverberatory chamber, a plate carrying 40 said transmitters and having openings around its edge permitting vibration of said plate freely, by allowing access of the air to and from the under part of the plate, said transmitters being in substantially the 45 same plane and means to change the character of the sound in each transmitter by a partition, dividing the reverberatory chamber adjacent each transmitter.

3. In a device of the kind described, the 50 combination of a plurality of transmitters, a vibrating plate carrying said transmitters, a cover spaced from the plate and partially inclosing the transmitters, means uniting said plate to the cover in said spaced relation with a non-metallic cushioning material therebetween, said plate having a plurality of openings therethrough into the inclosure adjacent each transmitter to enable said plate to vibrate freely and to allow a flow 55 of air into said inclosure formed by the plate and cover during such vibration.

In testimony whereof, I have signed my name to this specification, in the presence of two subscribing witnesses.

CHARLES E. WILLIAMS.
